Greensboro, N.C., a corporation of Delaware

Filed Feb. 26, 1968, Ser. No. 10,724

Term of patent 14 years

Int. Cl. D2—02

U.S. Cl. D2—7

FIG. 1 is a front elevational view of a knit panty hose showing our new design, the appearance of the knit of the panty portion and that of the hose portion being uniform throughout, the fabric symbols indicating a more dense or opaque panty portion which joins with a less dense or sheer leg portions along an unseamed juncture. The dotted lines indicate seams.

FIG. 2 is a side elevational view of the design shown in FIG. 1;

FIG. 3 is a rear elevational view thereof; and

FIG. 4 is an enlarged fragmentary view of the portion where the panty portion and the hose portion join.

We claim:

The ornamental design for a knit panty hose, as shown and described.
